UNITED STATES PATENT OFFICE

JOSEPH J. DARLINGTON, OF WINSTON-SALEM, NORTH CAROLINA

ELECTRICAL FLASH LIGHT

Application filed August 7, 1928. Serial No. 297,992.

This invention relates to electrical flash lights and more particularly to a flash light especially adapted for use by police, watchmen, and the like.

5 An important object of the invention is to provide a flash light which is extensible so that the reflector and the illuminating element may be disposed at a considerable distance from the body of the operator and will, 10 therefore, give no indication to criminals of the location of the operator of a search light.

A further object of the invention is to provide in a structure of this character an arrangement such that while the light is extensible to a considerable distance from the hand of the operator, the control switch therefor is conveniently disposed and readily accessible.

20 A further object of the invention is to provide a construction in a device of this character permitting use of the light as an ordinary flash light and permitting a construction which will not exceed in bulk to an appreciable extent, the ordinary flash light construction.

25 These and other objects I attain by the construction shown in the accompanying drawings, wherein for the purpose of illustration is shown a preferred embodiment of my invention and wherein:

Figure 1 is a side elevation of a flash light constructed in accordance with my invention, the reflector element being shown in solid lines in the position which it occupies 35 when initially extended and in dotted lines in the position which it occupies in use;

Figure 2 is a sectional view through the flash light showing the reflector in the position which it normally occupies;

40 Figure 3 is a section on the line 3-3 of Figure 2;

Figure 4 is a section on the line 4-4 of Figure 2;

45 Figure 5 is a fragmentary side elevation showing the reflector in its extended operative position;

Figure 6 is a wiring diagram showing the connections employed.

Referring now more particularly to the 50 drawings, the flash light includes the usual

barrel 10 and reflector 11 which is threaded upon the forward end of the barrel. The barrel is preferably tubularly formed and adjacent the end thereof to which the reflector 11 is secured has openings 12 formed therein 55 with which communicate the inner open ends of radially projecting casings 13. These casings are of a size to receive the usual flat flash light cell and have hinged outer ends 14 provided with snap catches 15 to permit ready 60 insertion and removal of the cell. In the arrangement at present disclosed, these cells are adapted for connection in parallel for use with the illuminating element 15 of the light and the barrel 10 has arranged interiorly 65 thereof an insulated connecting bus element 16 for connecting like terminals of the cells. The remaining contact elements of the cells in this arrangement may be directly electrically connected with the wall of the barrel 70 which forms one side of the circuit. Obviously, a slight modification of this arrangement will be necessary to employ the battery in series with one another.

Adjacent the opposite end of the barrel is 75 a suitable support 17 to which is secured one end element 18 of a tapered telescopic tube 19. The opposite end element 20 of this tube is provided with a fork 21 having hooked ends 22 engaging in diametrically opposed 80 openings formed in a skirt 23 disposed inwardly of the threaded parallel engaging flange 24 of the reflector. The end and intermediate elements of the telescopic tube 9 are of frusto-conical formation, are arranged 85 in nested relation within the barrel 10, and frictionally engage each other when in extended relation to provide a rigid support for the reflector 11. The reflector 11 is arranged at one end of this support and the barrel 10 90 is arranged at the other end thereof, and the barrel constitutes a handle for the support.

It will be obvious that this fork will enable the disposition of the reflector, when disengaged from the barrel, at a desired angle 95 to the telescopic tube 19 and accordingly to the barrel and, at the same time, the reflector casing will be electrically connected to the barrel either directly or through this fork, the tube 19 and support 17. Arranged be- 100

tween the end cap 25 of the barrel at the last named end thereof and the support 17 is a transversely extending axle 25 which is insulated from the barrel and supports a 5 spring drum casing 26. This drum casing has wound upon the drum thereof which is electrically connected to the axle a lead wire 27 which is extended through the tubular telescopic rod and secured to a contact element 10 28 carried by the reflector insulated from the casing thereof and adapted for engagement with the base contact of the illuminating element 15. The axle 25 is connected by an insulated lead wire 28 with one contact 29 of a 15 switch 30, the opposite contact of which is connected with the bus element 16. It will be obvious that this switch which is carried by the barrel and insulated therefrom will control operation of the illuminating element 20 15, so that it is possible, by rotating the reflector, to release the same from the barrel and extend the same for a considerable distance from the barrel by extending the tubular telescopic rod 19. The reflector may then be disposed at a convenient angle and when the 25 illuminating element is in operation, it will not give any indication of the location of the operator.

It will also be obvious that the construction 30 hereinbefore set forth is capable of a certain range of change and modification without materially departing from the spirit of the invention and I accordingly do not limit myself to such specific structure except as 35 hereinafter claimed.

I claim:

1. In a flash light, a barrel, a reflector removably threaded upon one end of the barrel, an illuminating element carried by the reflector, and a telescopic support for the reflector permitting rotation thereof to engage or disengage the same with respect to the barrel, said support collapsing into the barrel, said barrel having radially extending casings projecting outwardly therefrom, said casings each having a hinged outer end and constituting receptacles for battery units to energize said illuminating element.

2. In a flash light, a barrel, a reflector removably threaded upon one end of the barrel, an illuminating element carried by the reflector, a telescopic support for the reflector permitting rotation thereof to engage or disengage the same with respect to the barrel, said support collapsing into the barrel, said barrel having radially extending casings projecting outwardly therefrom, said casings each having a hinged outer end and constituting receptacles for battery units to energize said illuminating element, the telescopic support being tubular and being electrically connected with one terminal of the illuminating element, and a lead wire connected with the second terminal of the illuminating element and extending through said support.

3. In a flash light, a barrel, a reflector removably threaded upon one end of the barrel, an illuminating element carried by the reflector, a telescopic support for the reflector permitting rotation thereof to engage or disengage the same with respect to the barrel, said support collapsing into the barrel, said barrel having radially extending casings projecting outwardly therefrom, said casings each having a hinged outer end and constituting receptacles for battery units to energize said illuminating element, the telescopic support being tubular and being electrically connected with one terminal of the illuminating element, a lead wire connected with the second terminal of the illuminating element and extending through said support, and a spring drum disposed within the barrel beneath the lower end of the support to which the lead wire is electrically and mechanically connected.

4. In a flash light, a barrel, a reflector removably threaded upon one end of the barrel, an illuminating element carried by the reflector, a telescopic support for the reflector permitting rotation thereof to engage or disengage the same with respect to the barrel, said support collapsing into the barrel, said barrel having radially extending casings projecting outwardly therefrom, said casings each having a hinged outer end and constituting receptacles for battery units to energize said illuminating element, the telescopic support being tubular and being electrically connected with one terminal of the illuminating element, a lead wire connected with the second terminal of the illuminating element and extending through said support, a spring drum disposed within the barrel beneath the lower end of the support to which the lead wire is electrically and mechanically connected, and means engaged by the battery units when inserted in said casings electrically connecting one terminal of each thereof to the telescopic support and the other terminal thereof to said spring drum.

5. In a portable flash light, a barrel, a reflector releasably engaged with the forward end of the barrel, an illuminating element carried by the reflector, a telescopic tube consisting of end and intermediate elements of frusto-conical formation and normally arranged in nested relation within the barrel, means securing one end element of said tube to the casing, and means securing the reflector to the other end element of said tube, said last end element and the intermediate elements of said tube being adapted when the elements are in extended relation to project through and beyond the forward end of the barrel and frictionally engage each other to provide a rigid support for the reflector, and said barrel being adapted to be used as a handle for the rigid support.

6. In a portable flash light, a barrel, a re-

reflector releasably engaged with the forward end of the barrel, an illuminating element carried by the reflector, a telescopic tube consisting of end and intermediate elements of frusto-conical formation and normally arranged in nested relation within the barrel, the forward ends of the nested elements of said tube being spaced rearwardly from the forward end of the barrel, means securing the rear end of one end element of said tube to the casing, and means pivotally securing the reflector to the forward end of the other end element of said tube and normally arranged within the barrel, said last end element and the intermediate elements of said tube being adapted when the elements are in extended relation to project through and beyond the forward end of the barrel and frictionally engage each other to provide a rigid support for the reflector, and said barrel being adapted to be used as a handle for the rigid support.

In testimony whereof I hereunto affix my signature.

JOSEPH J. DARLINGTON.
